UNITED STATES PATENT OFFICE.

JOHN NELSON, OF OTTAWA, KANSAS.

DISPLAY RAIL.

1,425,211.

Specification of Letters Patent. Patented Aug. 8, 1922.

Application filed March 29, 1922. Serial No. 547,692.

To all whom it may concern:

Be it known that I, JOHN NELSON, a citizen of the United States of America, residing at Ottawa, in the county of Franklin 5 and State of Kansas, have invented certain new and useful Improvements in Display Rails, of which the following is a specification.

This invention relates to certain new and 10 useful improvements in display rails for wood beds, particularly employed for displaying beds in windows of furniture stores without the necessity of requiring a great amount of space as would be necessary 15 through the employment of the regular side rails provided for the bed when in use.

The primary object of the invention is to 20 provide a display rail of the above kind that will be simple and inexpensive in construction and capable of being rapidly applied as well as embodying extreme strength and durability.

Another object of the invention is to provide a display rail for beds of generally 25 simplified and improved form.

With the above general objects in view 30 the invention consists of the novel combination and arrangement of parts hereinafter more fully described in connection with accompanying drawings, and in which like 35 reference characters designate corresponding parts through the several views.

In the drawings:—

Figure 1 is a side elevational view, 35 partly broken away and in sections, of the head and foot members of a wooden bed connected by a display rail constructed in accordance with the present invention,

Figure 2 is an enlarged side elevational 40 view of the display rail shown in Figure 1, the normal form of the blanks from which the rail is formed being indicated by dotted lines,

Figure 3 is a view similar to Figure 2 of 45 the device shown in Figure 2 in top plan,

Figure 4 is a horizontal sectional view taken on line 4—4 of Figure 2,

Figure 5 is a view similar to Figure 2 looking at the opposite side of the rail.

Referring more in detail to the several 50 views, the present invention contemplates the provision of a simple, efficient and durable form of short display rail for rigidly operatively connecting the head member

55 5 and foot member 6 of a wooden bed, which head and foot members are recessed near

their lower ends as at 7 in the posts thereof and provided with transverse pins 8 in said recesses adapted to be engaged by hook members of bed rails in the usual manner. 60

In accordance with the invention, a rail is stamped from a sheet of metal to provide the body portion 9 of the display rail, the marginal portions of which are shown unfolded by dotted lines in Figure 2 at 10, 65 which marginal portions are bent at right angles to the blank proper so as to provide the body portion of pan shape with marginal reinforcing flanges so that a neat appearance is had and the device greatly strengthened. 70 These marginal flanges 10 are provided at right angles to the body of the blank at all sides as shown.

The sheet metal blank is also initially stamped to provide oppositely extending 75 end hook members 11 integral with the body portion 9 and having the inclined inner edges thereof adapted to ride on the inner sides of the pins 8 so that the hook members 11 may be wedged tightly in place so as to 80 effectively connect the head and foot members 5 and 6 of the bed.

As shown clearly in Figures 4 and 5, the hook members 11 are preferably located in a plane substantially midway between the 85 body portion 9 and the free edges of the flanges 10 by laterally or inwardly offsetting said hook members as at 13.

In the preferred form of the device, the body portion is of rectangular form in side 90 elevation so as to squarely abut the inner faces of the posts of the head and foot members 5 and 6 as indicated generally by the numeral 14 so that said head and foot members are effectively steadied when connected 95 by the present device.

In the use of the invention one display rail is employed at each side of the head and foot members 5 and 6 and the device is arranged with the flanges 10 projecting inwardly so that it will be seen that Figure 2 is an outside view while Figure 5 is an inside view of the rail. Obviously, there is no right and left hand rail as all of the rails constructed in accordance with the present 100 invention may be employed at either side of the bed, and as the device embodies a single sheet metal member simplicity is had and no adjustment required for the placing of the invention into use. 110

From the foregoing description, it is believed that the construction and operation

as well as the advantages of the present invention will be readily understood and appreciated by those skilled in the art.

Minor changes may be made without departing from the spirit and scope of the invention as hereinafter claimed.

What I claim as new is:—

1. In a display rail for beds, wherein said rail is struck from a single sheet of material, 10 and wherein end hooks are carried by the rail for perpendicularly supporting head and foot members of beds, said rail being of

rectangular formation in plan view and having marginal reinforcing flanges.

2. In a display rail for beds, wherein said rail is struck from a single sheet of metal, 15 and wherein end hooks are carried by the rail for perpendicularly supporting head and foot members of beds, said rail being of rectangular formation in plan view and 20 having marginal flanges bent therefrom and extending from the same side of the rail.

In testimony whereof I affix my signature.
JOHN NELSON.
